UNITED STATES PATENT OFFICE

ARTHUR H. ROSS, OF SAN LEANDRO, CALIFORNIA

AEROPLANE

Application filed January 21, 1928. Serial No. 248,405.

The present invention relates to aeroplanes and has for its object to provide a structure which is capable of flotation on water and has means incorporated therein so that water may 5 be taken into a compartment formed in the tail for the purpose of giving the plane proper equilibrium on the water. It is now the common practice to mount the heavier portions of 10 an aeroplane such as the engine in the nose thereof while the tail carries comparatively little weight. The result is that if an aeroplane lands on the water it has a tendency to nose downwardly but with my improvement sufficient water is taken in the tail to overcome this tendency.

Another very important object of the invention resides in the provision of an aeroplane which has the engine and gasoline tank so arranged therein as to give the proper 20 equilibrium to the aeroplane when flying.

Another very important object of the invention resides in the provision of wings of hollow construction for containing a supply of helium and the heating of the helium so as 25 to attain maximum efficiency.

A still further very important object of the invention resides in the provision of an aeroplane of this nature which is comparatively simple in its construction, strong and durable, 30 thoroughly efficient and reliable in operation, and otherwise well adapted to the purpose for which it is designed.

With the above and numerous other objects 35 in view as will appear as the description proceeds the invention resides in certain novel features of construction, and in the combination and arrangement of parts as will be hereinafter more fully described and claimed.

In the drawings:

Figure 1 is a side elevation of an aeroplane embodying the features of my invention,

Figure 2 is a fragmentary detail transverse section taken substantially on the line 45 2-2 of Figure 1,

Figure 3 is an enlarged detail section taken substantially on the line 3-3 of Figure 1,

Figure 4 is a vertical longitudinal section through the aeroplane,

Figure 5 is an enlarged detail section showing the water receiving compartment of the tail, and

Figure 6 is an enlarged detail section taken substantially on the line 6-6 of Figure 1.

Referring to the drawings in detail it will be seen that the fuselage F is of the stream line type comprising the nose 5, the operator's compartment 6 and the tail 7. The aeroplane illustrated herein is of the monoplane type but I do not wish to be limited to this particular type. The wings 8 are hollow as illustrated to advantage in Figure 3 so that a supply of helium may be stored therein. The passenger compartment 6 has a doorway 10 formed therein with a door 11 that may be held tightly therein as is illustrated to advantage in Figure 6. The door is provided with interior offset flanges 12 so that packing 13 may be placed thereon to engage the interior surface of the fuselage easily about the doorway 10. Bearings 14 are disposed on the offset flanges 12 and rockably receive a shaft 15 having cams 16 on the ends thereof to engage in brackets 17 on the inside of the compartment 6. A crank 18 is provided at the center of the shaft 15 for manipulation thereof. The compartment 6 is also provided with a plurality of port holes 20 which may be closed by transparent port closures 21 which are held in place by crank shafts 22 having cams 23 to engage flanges 24 and hold them with their packing 25 tightly against the interior surface of the compartment. The crank shafts are rockable in bearings 26. An engine 27 is mounted in the nose for driving propeller 28. A gasoline tank 29 is mounted on the lower portion of the nose and a vacuum system 30 connects the tank 29 with the carburetor of the engine. A reserve gasoline tank 31 is mounted in the tail immediately to

60

90

the rear of the compartment 6 and is connected by a pipe 32 with the tank 29 and a valve 33 is mounted in the pipe 32 and operable from an accessible position to the aviator.

5 A filler pipe 34 rising from the tank 31 so as to be accessible from the top of the tail. The partition 35 is provided longitudinally of the tail 7 to form a compartment 36. The portion of the tail wall about the compartment 36 10 is formed with openings 37 for receiving plates 38 having openings 39 therein and cages 40 thereon for projecting inwardly of the compartment 36. Ball valves 41 are mounted in the cages 40 to close the openings 39 15 normally by gravitation.

When the aeroplane lands on the water it will be seen that the compartment 36 will fill because the ball valves 41 are constructed of cork or some other floatable material. The 20 water trapped in the compartment 36 will give the proper stability to the aeroplane on the water to overcome the weight of the engine 27 and other heavier parts located at the front thereof.

25 A pipe 42 leading from the exhaust of the engine 27 is led through the wings 8.

The heat from the pipe 42 will heat the helium and increase the effectiveness thereof.

Control wires 24 for the rudder 45 and 30 other elements lead through the fuselage to the control sticks 46.

It is thought that a clear understanding of the main proportions of the aeroplane will now be understood. The compartment 6 is 35 defined by partitions 47 and 48 which terminate a distance from the top of the compartment so that access may be had to the tail and to the nose for obvious purposes. A port 20' is provided in the top of the compartment 6 40 and has a hinged port closure 21' mounted therein so that the same may be opened when the fuselage is floating on the water so that the occupants in the compartment may have proper air.

45 The present embodiment of the invention has been disclosed in considerable detail merely by way of example since in actual practice it attains the features of advantage enumerated as desirable in the statement of 50 the invention and the above description. It will be apparent that changes in the details of construction, and in the combination and arrangement of parts may be resorted to without departing from the spirit or scope of 55 the invention as hereinafter claimed or sacrificing any of its advantages.

Having thus described my invention, what I claim as new is:

60 In an aeroplane structure comprising a fuselage, a partition in the fuselage at the tail portion thereof to form a compartment extending longitudinally along the bottom thereof, said tail having openings leading in the compartment thus formed, plates in said 65 openings with cages extending inwardly

therefrom, said plates having openings and balls in the cages closable on said openings of the plate, said balls being portable, wings projecting laterally from the sides of the fuselage and being of hollow construction to hold a supply of lighter than air gas, an internal combustion engine mounted in the nose of said fuselage, and pipes leading from the exhaust of the engine through said wings adjacent the forward sides thereof to heat 70 the gas therein. 75

In testimony whereof I affix my signature.

ARTHUR H. ROSS.
